(57) **CLAIM**

The ornamental design for a boot rack and mitten clasp combination, as shown and described.

DESCRIPTION

FIG. 1 is a front elevated view of a boot rack and mitten clasp combination showing my new design.

FIG. 2 is a side elevated view of the boot rack and mitten clasp combination.

FIG. 3 is a top plan view of the boot rack and mitten clasp combination.

FIG. 4 is a bottom plan view of the boot rack and mitten clasp combination; and,

FIG. 5 is a front perspective view of the boot rack and mitten clasp combination.

The broken lines are for illustrative purposes only and form no part of the claimed design.
